UNITED STATES PATENT OFFICE

2,461,786

FLUORESCENT LIGHTING FIXTURE

Joseph Terr, Cleveland, Ohio, assignor to Holden-line Company, Cleveland, Ohio, a corporation of Ohio

Application October 16, 1946, Serial No. 703,692

3 Claims. (Cl. 248—343)

1

My invention relates to fluorescent lighting fixtures and relates more particularly to improvements in the method and means of hanging fluorescent lighting fixtures of the type which are adapted to be suspended from a ceiling.

At present fluorescent fixtures of this type which are suspended from the ceiling by means of tubes offer considerable difficulty and danger in hanging for use and in the heavier types require an erector and helper to hang the fixture safely while the necessary connections of the fixture leads are being made to the electric service lines. In commercial and in industrial uses such fluorescent lighting fixtures are bulky and heavy and are awkward to handle, especially if the supporting members are properly spaced for rigidity and stability. The common practice is to support the fixture from a steel strap which is mounted to an outlet box in the ceiling of the area to be lighted. Before securing the fixture to the strap it is necessary to connect the leads from the fixture to the service lines. This entails cutting and splicing the wires and soldering, taping, etc. While this is being done, the fixture must be supported by the electrician and/or his helper. After the electric connections are properly made, the supporting tubes are passed through holes in the strap and finally locked up. The method is time consuming and dangerous.

It is therefore highly desirable to achieve a means of hanging heavy, bulky lighting fixtures in a safe, quick and economical manner in which the fixture can be easily and safely supported, releasing the erector to make the splicing of the fixture leads to the service lines.

More specifically my invention relates to an ensemble and method for simply and easily hanging fluorescent lighting fixtures and the like.

In accordance with the foregoing it is an object of my invention to provide a means for easily supporting the lighting fixture before the wire splices are made so that the electrician hanging the fixture can work safely with both hands free.

Another object of my invention is to provide a safe and improved means for hanging the lighting fixture and supporting it by the mounting strap.

A further object of my invention is to provide a simple lock-up of the canopy or housing, with easy means for final aligning of fixture and housing. Other objects and advantages of this invention will be apparent during the course of the following description.

2

In accompanying drawings, forming a part of this specification and in which like numerals are employed to designate like parts throughout the same:

6 Figure 1 is an elevation view partly in section of a preferred embodiment of my invention showing the first step in mounting the lighting fixture;

10 Figure 2 is an enlarged fragmentary view taken from the line B—B of Figure 1;

Figure 3 is an enlarged fragmentary sectional view taken from the line C—C of Figure 1;

Figure 4 is a fragmentary detail view taken from the line D—D of Figure 1;

15 Figure 5 is a top plan view of the hanger strap of Figure 1;

Figure 6 is a perspective view of a fluorescent lighting fixture in which the means and method of hanging of my invention is illustrated;

20 Figure 7 is an elevational view partly in section showing the completed assembly of the mounting of my invention;

Figure 8 is a detail view of the underside of the hanger strap of my invention;

25 Figure 9 is a view similar to that of Figure 8 taken of the upper end of the hanger strap of my invention;

Figure 10 is a view taken on the line E—E of Figure 7;

30 Figure 11 is a view taken on the line F—F of Figure 7;

Figure 12 is a fragmentary elevational view partly in section, of another embodiment of my invention.

35 Referring now to the drawings, in all of which like parts are designated by like reference characters, Figs. 1 and 5 best illustrate the improved mounting strap 10 of my invention, adapted for use with fluorescent lighting fixtures. As shown,

40 said strap is preferably formed from an elongated flat bar or strap of steel having an inversely cupped perforated central portion 15 and provided with a pair of oval embossings 14 disposed at either end of the strap, each embossing intersected by a rectangularly shaped slot 11 symmetrically located with respect to the center line of the strap, each slot adapted to receive one of a pair of cylindrical tubes 30 and each embossing adapted to seat lips 33 of each of the oppositely disposed tubes 30 (see Fig. 11).

45 The centrally disposed circular perforation 12 provided in the central cup shaped portion of the strap is adapted to receive a service wiring connection for mounting the strap 10 to a service outlet box 50 and an oval formed embossing

15' surrounds the perforation 12 and thus strengthens the strap at its point of maximum load. The depth of the cupped central portion 15 is determined by the depth of the stepped down sides 16 of the cup and is such that sufficient clearance is provided when the strap 10 is locked, by means of the connections comprising the threaded nipple 53 of the hickey 51 and the nut 54, to the outlet 50 (see Fig. 7).

On either side of the central portion of the strap, a relatively narrow elongated slot 13 is interposed between the relatively larger slot 11 and the stepped sides 16 and said slot is provided as a means of reenforcing the central mounting as well as for other purposes, later described herein.

The mounting strap 10 of my invention is adapted to be covered by a canopy or housing member 20 provided with a cylindrical perforation 21 at either end of the same, which is symmetrically located with respect to the center line, through which the tubes 30 are passed. Said canopy is preferably formed as a shallow rectangular pan having relatively narrow side walls 70 and a relatively flat bottom portion 71, the said perforations 21 being formed at either end in the bottom surface 71 of the canopy member 20, and said canopy is of such width and length as to cover the strap 10 and outlet box 50 when the lighting fixture is in its complete assembled position, as shown in Figs. 6 and 7.

The canopy 20 is preferably provided with a pair of rectangular embossings 22 surrounding the apertures 21, said embossings being of sufficient overall length and width to receive and cover the embossings 14 disposed at either end of the strap 10. The said canopy or housing 20 may be further enhanced by decorative configuration but this does not constitute an essential part of the present invention.

A pair of suspension or hanger tubes 30 are shown in the drawings herein, said tubes being preferably cylindrical in form, as shown, and provided with lips 33 at the upper ends thereof as by swaging or the like, said lips extending in opposite directions and preferably formed with a spherical contour and no wider than the outside diameter of the tubes 30 as taken on an axis 90° to the lips to form a self-aligning feature of the tubes.

These tubes are adapted to carry fixture leads 56 from the fixtures to the outlet box connections and the same are screwed into the fixture body in the conventional manner.

Each tube is further preferably provided with a metal slipon ring 31 having a set screw 32 engaged in a tapped hole in the ring. The slipon ring provides a simple means for locking the housing or canopy into final position over the strap 10, as later described. It will be noted that the perforations or slots 11 are preferably of such width that the tubes 30 may pass therethrough when they enter the slots 11 with the extended lips on the tubes disposed, as illustrated in Fig. 9. In installing a fluorescent fixture with the improved structure of my invention, the canopy 20 and the slip rings 31 are placed on the tubes 30, as shown in Fig. 1, the two tubes being securely screwed into the fluorescent fixture in the conventional manner with the two leads 56 coming through one of the tubes, this being the left hand tube of Fig. 1.

The strap 10 is then mounted on the outlet box 50, as shown in Figs. 1 and 7, the fixture then

being lifted up into place with the tubes 30 facing, as shown in Fig. 2, and fed through the slots 11 in the strap 10. A quarter turn of each tube 30 then brings the axis of the lips 33, as shown in Figs. 10 and 11, in line with the axis of the embossings 14 and releasing the fixture will seat the tubes within the said wells or embossings 14. The outer edge of the slots 11 are so positioned that when the tubes are seated in the wells 14, the 10 said tubes are aligned to conform to a predetermined spacing in the lighting fixture "F" wherefore the fixture is amply and safely supported while the electrician makes the electrical splice of the lead wires 56 to the service lines 57, 15 the strap making it possible for the lighting fixture to be brought directly into the lock up position and to firmly hold it there, leaving both hands of the electrician or maintenance erector free to make the electrical connections or final 20 alignment by means of the lock nut 54.

It will be noted that the secured seating of the tubes by means of the lips 33 in the recesses 14 permanently secures the suspension tube 30 and prevents rotation of the tubes due to any extraneous vibrations or other causes, acting in the manner of a safety lock.

After the electrical splice is made, the strap 10 and tubes 30 are then brought into their final position, as illustrated in Fig. 7, where the tubes 30 are brought into position by slightly bringing the tubes inwardly on the axes indicated at 35a and 36, then aligning the tubes in parallel alignment so that the axes of the said tubes 30 are parallel as indicated at 35 and 36a.

The canopy 20 is next brought close to the ceiling, as shown in Fig. 7, by bringing the slip rings 31 up close to the underside of said canopy and by tightening the set screws 32 wherefore the canopy is locked in final position and the hanging 40 complete.

The modification of my invention, as shown in Fig. 12, represents an embodiment wherein the fixture is fastened to the ceiling 40 by means of bolts or screws 47 projected through the elongated slots 13, said elongated slots providing a wide range for spacing of the mounting screws or bolts 47.

While I have disclosed my invention in connection with a preferred embodiment, numerous and extensive departures may be made from the form of my invention herein illustrated and described without however departing from the spirit of my invention and the scope of the appended 55 claims.

I claim:

1. An improved mounting means for lighting fixtures of the suspension type, comprising generally rectangular elongated flat strap means having a centrally apertured inversely shaped cup portion, said strap being provided with a pair of recessed seating wells, one at either end thereof, an opening at either end of said strap adapted to be keyed with one of said wells and disposed at right angles thereto, a pair of tubular suspension members, an end of each adapted to be telescoped through one of said opposite end openings and to be rotated into alignment with said associated well, wherefore the suspension member may be supported by said strap means.

2. An improved mounting means for lighting fixtures of the suspension type, comprising strap means having a centrally apertured inversely cupped portion, said strap being provided with a pair of recessed wells at either end thereof, an 70 opening contiguous to each well and adapted to

be keyed with said well and disposed at right angles thereto, a pair of tubular suspension members, an end of each adapted to be telescoped to one of said opposite end openings and to be brought into alignment with the recessed well for seating therein, said suspension members carrying a lighting fixture at the opposite ends thereof, wherefore the suspension members and lighting fixtures are securely supported by said strap means.

3. An improved method for mounting lighting fixtures of the suspension type described comprising rotatably securing a pair of suspension hangers to the lamp holder portion of the fixture, slideably telescoping a canopy over said hangers, securing a strap member to a ceiling contained outlet box, projecting each of the upper ends of said hanger through one of a pair of perforations disposed at either end of said strap in predetermined spacing related to the spacing of said hangers, giving said hangers a one-quarter turn to seat said hangers in depressed seats intersect-

ing said perforations wherefor said hangers are in secure seating engagement therewith, connecting the service and lead wires, the service wires projecting from the outlet box and the lead wires being conducted thereto from the lamp holder portion of the fixture, bringing the strap and its secured hanger and dependent fixture members to its final ceiling associated position, adjusting the canopy in its final outlet box and strap covering position.

JOSEPH TERR.
